US00D749210S

(12) **United States Design Patent**
Appelbaum et al.

(10) **Patent No.:** US D749,210 S
(45) **Date of Patent:** ** Feb. 9, 2016

(54) **PROBE HOLDER**

(71) Applicant: **Novian Health Inc.**, Chicago, IL (US)

(72) Inventors: **Henry R. Appelbaum**, Chicago, IL (US); **William F. Graveman**, Tonganoxie, KS (US); **Julian Itzcovitz**, Neuilly sur Seine (FR)

(73) Assignee: **Novian Health Inc.**, Chicago, IL (US)

(**) Term: **15 Years**

(21) Appl. No.: **29/527,319**

(22) Filed: **May 18, 2015**

(57) **CLAIM**

The ornamental design for a probe holder, as shown and described herein.

DESCRIPTION

FIG. 1 is a front perspective view of a probe holder of our new design;

FIG. 2 is a front view of the probe holder;

FIG. 3 is a rear view of the probe holder;

FIG. 4 is a right side view of the probe holder;

FIG. 5 is a left side view of the probe holder;

FIG. 6 is a top plan view of the probe holder; and,

FIG. 7 is a bottom plan view of the probe holder.

The broken lines shown in FIGS. 1-7 illustrate portions of the probe holder that form no part of the claimed design.

1 Claim, 5 Drawing Sheets
